(57) **CLAIM**

The ornamental design for a steam pipe plate, as shown and described.

DESCRIPTION

FIG. 1 is a rear perspective view of a steam pipe plate showing our new design;

FIG. 2 is a front perspective view thereof;

FIG. 3 is a rear elevation view thereof;

FIG. 4 is a front elevation view thereof;

FIG. 5 is a right side elevation view thereof;

FIG. 6 is a left side elevation view thereof;

FIG. 7 is a top plan view thereof;

FIG. 8 is bottom plan view thereof; and,

FIG. 9 is a cross-sectional view of the steam pipe plate taken along line '9-9' shown in FIG. 3.

The broken lines illustrate portions of the steam pipe plate that form no part of the claimed design.
